UNITED STATES PATENT OFFICE.

TRIMBLE DE RODE, OF NEW YORK, N. Y.

MINING APPARATUS.

1,226,065.

Specification of Letters Patent.

Patented May 15, 1917.

Application filed February 29, 1912. Serial No. 680,618.

To all whom it may concern:

Be it known that I, TRIMBLE DE RODE, a subject of the Queen of the Netherlands, residing in the city, county, and State of New York, have invented certain new and useful Improvements in Mining Apparatus, of which the following is a full, clear, and exact description.

My invention relates to an improved apparatus to be used in connection with mining, and particularly in connection with a new method of mining set forth in detail and claimed in my companion application filed February 29, 1912, Serial No. 680,617.

15 In the drawings,

Figure 1 is a horizontal section illustrating conventionally the first step of my improved process.

Fig. 2 is a vertical section of the same.

20 Figs. 3, 5, 7, 9, 11 and 13 are horizontal sectional views of progressive steps.

Figs. 4, 6, 8, 10, 12 and 14 are vertical sectional views of Figs. 3, 5, 7, 9, 11 and 13, respectively.

25 Fig. 15 is a relatively enlarged detail view, conventional in character, of the shield or bulkhead and some of the apparatus therein employed in carrying out my improved method.

30 Fig. 16 is a side elevation, partly in section, of the same apparatus, certain parts being omitted, or not seen.

Fig. 17 is a plan view with the shield partly in section, on a horizontal plane.

35 Fig. 18 is a front elevation of the same apparatus partly in section.

At the outset I will describe in a general way my improved method of mining which comprises forming a cut in the material to

40 be mined; placing therein a suitable shield or bulkhead having in advance thereof a working space fitted with suitable apparatus for performing the mining operation; advancing said bulkhead or shield and forming

45 an outlet passage to the rear thereof of less cross sectional area than the cross sectional area of the said working space and directing said shield in any desired course through the material to be excavated, refining and separating the material excavated as the

50 work of excavation progresses. As shown in the drawings, Figs. 1 to 14, such an apparatus may be caused to traverse completely a large tract of mining material

55 while that part of the material actually removed to the surface represents a very small

part of the material actually mined or operated on since the major part of the separated material is deposited behind the advancing shield; the minor part of said material, for example the coarser part, is removed through the primary outlet passage to a point outside of the entrance to the mine. Such a process is of material value when employed in an anti-debris section 60 wherein there are objections to discharging from the mine the finer debris that tends to operate as a nuisance. The apparatus herein described comprehends such means as is necessary to extract the values of the material and separate and manipulate the balance in the manner heretofore referred to.

In the drawings, 7 represents the ladder of a digger which constitutes the preferable means for the main excavating work. This 75 ladder is hinged at 7^a and may be provided with a suitable number of mechanically actuated excavating buckets 7^b. 7^c—7^d are levers pivotally connected together, the former being also connected to the ladder 7, 80 the latter being also pivotally mounted at 7^e. 7^f is a chain suitably driven and connected with the levers 7^c—7^d to elevate the ladder 7. The entire digger thus described is mounted on a suitable carriage which is 85 arranged to traverse a track 7^g whereby said carriage may be moved transversely within the shield or bulkhead and so that the ladder 7 or digger will have the widest possible range of movement. The various details 90 of construction for operating and driving the latter may be modified in a variety of ways unnecessary to describe herein. As hereinbefore stated, the material excavated is separated and refined as the work of excavation progresses. These latter means are included in an apparatus whereby a portion of the excavated material is divided, portions being subsequently deposited in the bore in rear of the bulkhead while other 95 portion eventually are conveyed out of the mine. Any suitable form of dividing apparatus may be employed, and as illustrative thereof numeral 8 conventionally represents a separating device for the excavated material while 14 represents a convenient pipe to convey the material excavated by the digger 7 to said separating device 8. 9 represents conventionally a refining apparatus to which material passes from the separating device 8. 10 conventionally represents a 100 sluice-way. 11 represents one end of a cas-

105

110

115

ing which constitutes one end of the primary passage which enters the bulkhead from the rear. In the preferred form the casing 11 enters the rear of the bulkhead 5 at one side of the center, as best seen in Fig. 17, and means 11^a is provided whereby the point of elevation where said casing enters said shield or bulkhead may be varied as exigencies require. 12 is a discharge pipe through which the material to be restrained is passed from the inside of the shield or bulkhead to a point outside of and to the rear thereof. 13 is a pipe which enters the shield from the rear, the purpose 15 of said pipe being to drain such excess water as may be contained in the restrained material at the rear of the bulkhead, said drain pipe 13 leading, for example, to the sluice box 10, as shown. 15 represents what 20 may be termed a packing or gland of any suitable construction arranged externally of the shield, the function of which is to prevent any excess of material to the rear of the bulkhead from leaking forward of 25 the bulkhead or shield. 16—16 are independently operable cutting lips suitably mounted at the front of the shield or bulkhead and arranged to be forced ahead into the material to be excavated or in the path 30 of movement of the edge of the shield. Means for forcing said lips ahead may comprise hydraulic rams 16^a. 17 conventionally represents driving wheels which may be of any suitable form and which are power 35 driven, as by a ram 17^a, the function of said wheels being to advance or aid in advancing the shield. 18 are hydraulic nozzles arranged to swing as shown adjacent to the lips 16 to facilitate cutting away the material 40 to be excavated in front of said lips. 19 represents a hydraulic supply pipe which communicates with any suitable source of power, for example, outside of the mine, said supply pipe 19 leading through the 45 primary passage within the casing 11. The shield or bulkhead referred to is constructed in the main preferably of two main parts; namely, a lower part 20 which is U-shaped in horizontal cross section, and an upper 50 part or roof 21 which surrounds the lower part 20 and overstands the same to form a roof to support the top wall or ceiling, thereby affording a thoroughly protected working space within said shield or bulkhead, open at the front for the work of excavating. 22 is a low secondary bulkhead which extends across the front of the lower 55 part 20 of the bulkhead, the function of said secondary bulkhead being to protect the floor of the working space against any 60 inrush of water or material; for example, in the event of a cave-in. The advantage of forming the shield or bulkhead of two sections 20—21 is apparent since in some instances it might be desirable to work the

cut to a higher or lower elevation, in which event the upper section 21 of the bulkhead or shield may be elevated or depressed in a horizontal plane, said parts being slidably mounted one on the other and equipped 70 with any suitable jacking means such, for example, as a hydraulic jack conventionally shown at 23. Suitable packings 24 may, of course, be provided between the overlapping portions of the shield members 20—21. 75 Likewise suitable packings 24 may be provided for the adjustable entrance at the rear of the bulkhead for the casing 11 of the primary entrance and exit passage. As shown in Fig. 17, the broadest part of the 80 shield or bulkhead is at the front end, the sides thereof converging toward the rear, the purpose being to make it possible to readily alter the direction or course of the shield as the work progresses. The line of 85 convergence of one side of the bulkhead is preferably upon an arc having its center at the opposite front edge of the bulkhead. The several lips 16 are provided with any suitable bearings; for example, anti-friction 90 rollers 16^b, see Fig. 17.

In the specification I have used the terms "bulkhead" and "shield" and in order that the distinction may be clearly understood and for the purposes of intelligently reading the following claims, it should be understood that by the term "bulkhead" I mean a means to stand to the rear of the line of work to advance therewith at a proper distance therefrom to furnish a 100 proper adequate space. By the term "shield" specifically, I mean means which primarily supports the overhead material and which may be so constructed as to extend to the rear of the working space so as 105 to also perform the function of the bulkhead aforesaid. Either and both of these means constitute protecting means to prevent material from flowing into or falling into the working space. 110

By the term "walls" as used, I intend to include either the top, rear, or side walls.

What I claim is:

1. In an apparatus for use in a bore or cut, a movable protecting means furnishing 115 a working space therein open at one end, a refining apparatus within said protecting means, and means for transferring and depositing the material excavated in the bore to the rear of and adjacent said protecting means as the latter is advanced to progressively refill said bore or cut. 120

2. In an apparatus for use in a bore or cut, a movable protecting means furnishing a 125 working space open at one end, means within said working space for separating the excavated material, and means for progressively depositing the finer part of said excavated material in the bore at the rear of the protecting means as the latter is ad- 130

- vanced to progressively refill said bore or cut, said protecting means having an outlet passage at the rear with means for moving the coarser excavated material through said passage. 5
3. In an apparatus for use in a bore or cut, a movable protecting means open at the front forming a working space, means for separating excavated material into fine and coarse grades, a refining apparatus within said protecting means coöperating with said separating means, and means for transferring and depositing the finer grade of the separated material in the bore to the rear of said protecting means as the latter is advanced to progressively refill said bore or cut. 10
4. In an apparatus for use in a bore or cut, a protecting means open at the front forming a working space, means for separating the excavated material within said working space into fine and coarse grades, and means for progressively depositing the finer grade in the bore to the rear of the protecting means to progressively refill said bore or cut, said protecting means having an outlet passage of less cross sectional area than the cross sectional area of the working space, and means for moving the coarser grade of material through said passage. 15
5. In an apparatus for use in a bore or cut, a protecting means furnishing a working space open at one end, means for separating the excavated material within said working space into fine and coarse grades, a refining apparatus coöperating with said separating means to treat part of the material separated thereby, means for progressively depositing the material from said refining apparatus in the bore to the rear of the protecting means, said protecting means having an outlet passage of less cross-sectional area than the cross-sectional area of the working space, and means for removing through said passage the part of the separated material not treated by said refining apparatus. 20
6. In an apparatus for mining, a protecting means furnishing a working space there-in open at the front, means for separating the excavated material within said protecting means, and means for hydraulically depositing the finer part of said excavated material at the rear of the protecting means, said protecting means having an outlet passage at the rear thereof, with hydraulic means for moving the coarser portion of said excavated material through said passage, and means for removing surplus water from the material to the rear of the protecting means. 25
7. In an apparatus for mining, a movable protecting means open at the front forming a working space, means for separating excavated material within said working space, a
- refining apparatus coöperating with said separating means to treat material separated thereby, means for hydraulically depositing the waste material from said refining apparatus to the rear of said protecting means as the latter is advanced, said protecting means having an outlet passage at the rear thereof of less cross-sectional area than the cross-sectional area of the working space, and hydraulic means for removing through said passage the part of the separated material not treated by said refining apparatus. 70
8. In an apparatus for use in a bore or cut, a protecting means forming a working space at one end, means at the front thereof to excavate material, means within said working space to separate the material excavated, means for progressively depositing the finer portion of said excavated material at the rear of the protecting means to refill said bore or cut, and means for moving the coarser part of the excavated material from said working space and from said bore or cut. 85
9. In an apparatus for use in a bore or cut, a protecting means forming a working space open at its front end, means at the front thereof for excavating material, means within said working space for separating the material excavated, a refining apparatus within said working space coöperating with said separating means to treat part of the material separated thereby, means for progressively depositing the waste material from said refining apparatus at the rear of said protecting means to refill said bore or cut, and means for removing from said working space the separated material not treated by said refining apparatus. 90
10. In an apparatus for mining, a protecting means for forming a working space open at its front end, means at the front thereof for excavating material, means within said working space for separating the material excavated, a refining apparatus within said working space coöperating with said separating means to treat material separated thereby, means for hydraulically depositing the waste material from said refining apparatus at the rear of said protecting means, means for hydraulically removing from said working space the separated material not treated by said refining apparatus, and means for removing surplus water from the material deposited to the rear of said protecting means. 105
11. In an apparatus for mining in a bore or cut, in combination, an excavating tool, a bulkhead provided with a shield portion and adapted to move toward the material to be excavated, a material dividing apparatus protected by said shield portion, and means adapted to deposit part of the divided material in the bore in rear of said bulkhead. 110
12. In an apparatus for mining in a bore or cut, a movable protecting means open at the front forming a working space, means for separating excavated material within said working space, a

12. In an apparatus for mining in a bore or cut, in combination, an excavating tool, a bulkhead adapted to move toward the material to be excavated, a material dividing apparatus in front of and protected by said bulkhead, and means adapted to deposit part of the divided material in the bore in rear of said bulkhead.

13. In an apparatus for mining in a bore or cut, in combination, an excavating tool, 10 a bulkhead provided with a shield portion and adapted to move toward the material to be excavated, a material dividing apparatus protected by said shield portion and movable therewith, and means adapted to deposit part of the divided material in the bore in rear of said bulkhead.

14. In an apparatus for mining in a bore or cut, in combination, an excavating tool, 20 a bulkhead provided with a shield portion and comprising relatively adjustable parts adapted to move toward the material to be excavated, a material dividing apparatus protected by said shield portion, and means adapted to deposit part of the divided material in the bore in rear of said bulkhead.

15. In an apparatus for mining in a bore or cut, in combination, an excavating tool, a bulkhead comprising transversely curved 30 roof and base portions adjustable relatively to each other adapted to move toward the material to be excavated, a material dividing apparatus intermediate said roof and base portions of said bulkhead, and 35 means adapted to deposit part of the divided material in the bore in rear of said bulkhead.

16. In an apparatus for mining in a bore or cut, in combination, an excavating tool, 40 a bulkhead comprising a transversely and longitudinally curved roof portion and a transversely curved base portion adjustable relatively to each other adapted to move toward the material to be excavated, a material dividing apparatus intermediate said roof and base portions of said bulkhead, and 45 means adapted to deposit part of the divided material in the bore in rear of said bulkhead.

50 17. In an apparatus for mining in a bore or cut, in combination, an excavating tool, a bulkhead provided with a shield portion and adapted to move toward the material to be excavated and having independently 55 movable cutting lips operable substantially longitudinally of said bore, a material dividing apparatus protected by said shield portion, and means adapted to deposit part of the divided material in the bore in rear of said bulkhead.

60 18. In an apparatus for mining in a bore or cut, in combination, an excavating tool, a bulkhead provided with a shield portion and adapted to move toward the material 65 to be excavated and having independently

movable cutting lips operable substantially longitudinally of said bore, a transverse gland on said bulkhead adapted to contact said bore, a material dividing apparatus movable with said shield, and means adapted to deposit part of the divided material in the bore in rear of said bulkhead.

19. In an apparatus for mining in a bore or cut, in combination, an excavating tool, a bulkhead adapted to move toward the 75 material to be excavated, a material dividing apparatus in front of said bulkhead, means adapted to deposit a portion of the divided material in the bore in rear of said bulkhead, and means whereby another 80 portion of said divided material may be conveyed past said material deposited in said bore.

20. In an apparatus for mining in a bore or cut, in combination, an excavating tool, 85 a bulkhead adapted to move toward the material to be excavated, a material dividing apparatus in front of said bulkhead, means adapted to deposit a portion of the divided material in the bore in rear of said 90 bulkhead, and means whereby another portion of said divided material may be conveyed past said material deposited in said bore, comprising a passageway communicating with said bulkhead and extending 95 rearwardly thereof.

21. In an apparatus for mining in a bore or cut, in combination, an excavating tool, a bulkhead adapted to move toward the material to be excavated, a material dividing 100 apparatus protected by and in front of said bulkhead, means adapted to deposit a portion of the divided material in the bore in rear of said bulkhead, and means whereby another portion of said divided material may be 105 conveyed past said material deposited in said bore, comprising a passageway communicating with said bulkhead at one side of the center thereof and extending rearwardly thereof.

110 22. In an apparatus for mining in a bore or cut, in combination, an excavating tool, a bulkhead adapted to move toward the material to be excavated, a material dividing apparatus, means adapted to deposit a 115 portion of the divided material in the bore in rear of said bulkhead, means whereby another portion of said divided material may be conveyed past said material deposited in said bore, comprising a passageway 120 communicating with said bulkhead and extending rearwardly thereof, and means adapted to establish a current of said other portion of said material through said passageway.

125 23. In an apparatus for mining in a bore or cut, in combination, an excavating tool, a bulkhead adapted to move toward the material to be excavated, a material dividing apparatus, means adapted to deposit a por- 130

tion of the divided material in the bore in rear of said bulkhead, and means whereby another portion of said divided material may be conveyed past said material deposited in said bore, comprising a passageway communicating with said bulkhead and extending rearwardly thereof, a pipe in said passageway adapted to discharge into said dividing apparatus, said dividing apparatus having means adapted to direct a portion of the divided material into said passageway with material discharged from said pipe.

24. In an apparatus for mining in a bore or cut, in combination, an excavating tool, a bulkhead adapted to move toward the material to be excavated, a material dividing apparatus, means adapted to deposit a portion of the divided material in the bore in rear of said bulkhead, comprising a pipe connected to the discharge end of said dividing apparatus and adapted to discharge into the bore in rear of said bulkhead, and means whereby another portion of said divided material may be conveyed past said material deposited in said bore.

25. In an apparatus for mining in a bore or cut, in combination, an excavating tool, a bulkhead adapted to move toward the material to be excavated, a material dividing

apparatus, means adapted to deposit a portion of the divided material in the bore in rear of said bulkhead, comprising a pipe connected to the discharge end of said dividing apparatus and adapted to discharge into the bore in rear of said bulkhead, a separate pipe adapted to lead from the deposited material into the space between said bulkhead and the head of said bore, and means whereby another portion of said divided material may be conveyed past said material deposited in said bore.

26. In an apparatus for mining in a bore or cut, in combination, an excavating tool, a bulkhead adapted to move toward the material to be excavated, a separating apparatus, a refining apparatus, a passageway leading through said bulkhead and extending rearwardly thereof, means adapted to establish a hydraulic current through said refining apparatus past said bulkhead to said bore in rear of said bulkhead, and means adapted to establish a hydraulic current from said separating apparatus through said passageway.
